COMBINED WATERING DEVICE AND FEEDER

Melvin L. Noble, Rte. 2, Godley, Tex. 76044

Filed Feb. 7, 1966, Ser. No. 953

Term of patent 14 years

(Cl. D12—2)

FIG. 1.

FIG. 2.

FIG. 3.

FIGURE 1 is a perspective view showing the front, side and top of a combined watering device and feeder according to my new design.

FIGURE 2 is a reduced scale perspective view of the back side and top, and

FIGURE 3 is a side elevational view.

The undisclosed side of the combined watering device and feeder is substantially the same in appearance as the side shown.

I claim:

The ornamental design for a combined watering device and feeder, substantially as shown and described.
